WASHING MACHINE.

Application filed March 3, 1922. Serial No. 540,733.

The primary object in the present invention is to provide a washing machine or receptacle in which the water and the goods being washed may be continuously agitated by forcing air under pressure at localized areas through a substantial body or amount of water in the receptacle, using a motor-driven air pump operating at high speed for that purpose. A further object is embodied in the air-distributing means and the incorporation of such means in a cement wash tub or tray, and in mounting a clothes wringer in a movable or slideable position upon the tub or tray and in operable connection with the motor used to drive the air pump, whereby washing of the goods may take place in one tray section and rinsing and other operations may be successively carried on step by step with facility and despatch in the adjoining section of the tub or tray.

In the drawings accompanying this application, Fig. 1 is a reduced view of a wash tub or tray constructed according to our invention, and Fig. 2 is a front elevation, partly in section, of the same tub or tray. Fig. 3 is a vertical cross section of the tray on line 3—3 of Fig. 2. Fig. 4 is a top view of a modified form of air distributing device.

The invention comprises an elongated receptacle, tub or wash tray 2, which is shown is molded of concrete and made with two transverse division walls 3 and 4 to provide three separate washing compartments 5, 6 and 7, respectively. The rear wall 8 is common to all these compartments and rises to a higher elevation than the division walls and supports the usual hot and cold water faucets 9. Drain outlets 10 are also provided for these compartments which are connected up in any suitable way, not shown, and the structure so far described is not considered new or novel. However, in building or assembling this structure it is our purpose to add or incorporate an air distributing device within the bottom of one or more of the said compartments, and in Figs. 1 and 2, we show a perforated sheet metal plate 11 embedded at its

edges within the concrete walls and resting flat upon the concrete bottom 12. This plate forms a false bottom having relatively small perforations 13 communicating with a series of tapering grooves or channels 14 stamped or pressed in its bottom side and radiating or branching from a common air intake and valved pipe connection 15 at the rear side of the compartment, substantially as shown in compartment 5 in Fig. 1. However, in the adjacent rinsing compartment 6 the false bottom consists of a flat perforated plate 16 resting upon raised portions 17 of the concrete bottom which in effect provides a shallow air distributing chamber 18 entirely beneath the false bottom with which an air pipe 19 is connected and adapted to deliver air into compartment 6 in substantially the same way as in the first compartment 5, but over a larger area or in many more localized places therein. The drain connections 10 are open to the spaces beneath the false bottoms, see Fig. 3, but these openings are plugged when the compartments are filled with water as in operations. The last compartment 7 is preferably not equipped with an air-distributing and delivery device, but in Fig. 4 we show a coil of perforated pipe 20 which may be introduced in this compartment or any of the others and connected up to the air pump 21 located on a shelf 22 beneath the middle compartment 6.

As shown, air pump 21 has a pipe connection with both pipes 15 and 19, and it should be noted that both pipes extend upwardly at the rear side of wall above the normal level of the body of water therein and thence extend through the wall and downwardly to the bottom of the compartment so that the water is trapped and can not flow back through these pipes to the pump, which may be of the rotary type or any other kind capable of producing a continuous flow of air of six to eight cubic feet per minute delivered through relatively small pipes 15 and 19.

Pump 21 is driven by an electric motor 22 and a clutch 23 which is adapted to be thrown on and off by a hand lever 24 pivot-

ally mounted upon a bracket affixed to the front leg 25 of the supporting frame for the wash tray. Motor 22 is also arranged to operate a wringer 26 which is supported to slide upon the parallel upper edges of the rear and front walls of the wash tray, the operating connections between the motor and the wringer being located at the rear side of the tray. Thus, a clutch 27 is adapted to connect and disconnect the motor shaft from a separate motor shaft extension having a bevel gear 28 meshing with a bevel gear 29 upon the lower end of a telescopic extensible shaft 30. The upper and lower sections of shaft 30 are journaled in separate swiveled angle brackets 31 and 32, respectively, and a bevel gear 33 for the upper shaft section meshes with a similar gear 34 at the rear end of horizontal shaft 35 carrying the upper rubber roller 36 of the wringer, see Fig. 3. Shaft 35 is journaled in and supported by a slideable bracket 37 which straddles the upper edge of rear wall 8 of the tray, and bracket 37 is adapted to be clamped rigidly in place, wherever shifted, by a thumb screw 38. In operations, the wringer is usually stationed directly above one or the other of the two division walls of the tray and may also be shifted to either end of the tray. The wringer comprises a pair of upright standards 40-41 joined by an inclined delivery board 39, said standards having curved overhanging ends within which shaft 35 has a rotatable bearing. The base portion 42 of each standard is extended lengthwise to seat upon the upper flat face of the cross walls of the tray, and a metal strap 43 also serves to unite the two standards rigidly together. A gravity catch 44 is swiveled in the base portion of the rear standard 41 to lock the wringer against movement when seated over one of the division walls 3, and the front standard 40 is also fastened in a stationary set position at these divisional places in the tray by a pair of angular clamping bolts 45-45 having thumb nuts 46 exposed at the front side of the tray. Bolts 45 extend through perforated enlargements at the opposite ends of the relatively long foot portions 47 forming an integral part of front standard 40, and the clamping ends of each bolt 45 when drawn tight against the front inclined wall of the tray clamp the depending flange 48 against said wall, see Fig. 5. On the other hand when the thumb nuts 46 are loosened, bolts 45 are free to swivel or turn and permit the gravity clamping ends to ride up and over the cross walls as the wringer is shifted lengthwise of the tray.

In a washing operation the goods are first placed in compartment 5 which has been filled to a suitable height with water containing soap or any other cleansing agent,

and a cover 62 (Fig. 2) is placed over the compartment in close proximity to the surface of the water but spaced apart therefrom and the goods within the water. The motor having been switched on it is only necessary then to throw in the pump clutch 23 whereupon a continuous stream of air is pumped into the bottom of compartment 5 where it is compelled to pass upward through the water wherever liberated at the perforation 13. As a result the water and goods are constantly agitated; the presence of the goods prevents the air from escaping on straight vertical lines through the water; the distribution of the air and the changing lines of force tend to move and shift the goods from place to place and to rub the folds of the goods together with frictional cleansing effect; foam and suds gather on the surface beneath the cover and the turbulent water disseminates it through the goods appearing on the surface; and a thorough and complete cleansing of the goods is obtained in a very short time. During this operation the wringer may be clamped to the tray above division wall 3, and at the end of the operation the goods may, if desired, be passed through the wringer to the rinsing compartment where air may also be admitted to agitate the water and goods upon opening air valve 19. When the goods are rinsed the wringer is shifted to the opposite end of compartment 6 above wall 4 where the rinsed goods may be passed through the wringer into compartment 7 preliminary to drying operations, and in shifting the wringer the extensible shaft 30 at the rear telescopes and swings to different angles. Obviously, washing and rinsing operations in the separate compartments and the wringing of goods may also proceed simultaneously. That is to say, while a batch of goods is being washed in the first compartment, another batch of goods may be undergoing a rinsing operation in the second compartment while the operator is passing rinsed goods through the wringer into the third compartment.

For the subject matter illustrated and described but not claimed herein, see our co-pending application, Serial No. 666,928, filed Oct. 6, 1923.

What we claim, is:

1. A washing apparatus, comprising a receptacle having a bottom with spaced perforations therein through which air under pressure is vertically delivered into said receptacle, said perforations being symmetrically arranged and widely separated to create separate localized areas of pressure in a body of water contained within said receptacle.

2. A washing apparatus, comprising a concrete receptacle having a series of air

distributing passages incorporated in its bottom, and spaced openings in open communication with said air passages, and a valved pipe connected with said air passages, said air openings being symmetrically arranged and widely separated to create separate localized areas of pressure in a body of water within said receptacle when air under pressure is delivered through said openings. 10

In testimony whereof we affix our signatures.
